DAVID HUTCHISON AND JOSEPH M. MOFFAT, BOTH OF SAME PLACE.

ROTARY SHUTTLE FOR SEWING-MACHINES.

SPECIFICATION forming part of Letters Patent No. 267,020, dated November 7, 1882.

Application filed February 24, 1882. (No model.)

To all whom it may concern:

Be it known that I, THOMAS B. ROBERTS, of Pittsburgh, in the county of Allegheny and State of Pennsylvania, have invented certain new and useful Improvements in Rotary Shuttles for Sewing-Machines; and I do hereby declare that the following is a full, clear, and exact description of the invention, which will enable others skilled in the art to which it appertains to make and use the same, reference being had to the accompanying drawings, which form a part of this specification, in which—

Figure 1 is an edge view of my shuttle. Figs. 2 and 3 are front and back views respectively. Fig. 4 shows in section the two parts separated with bobbin and tension in position. Fig. 6 shows the blank for tension and thread-guide. Fig. 7 is a front view of same bent to shape. Fig. 8 is an edge view of same. Fig. 20 is an enlarged section of shuttle without bobbin or tension.

This invention relates to the construction of sewing-machine shuttles of the class known as "rotary" shuttles; and it consists in the construction and combination of parts, substantially as hereinafter fully described and claimed.

This shuttle is in two parts, which are attachable together, hollow inside, and carrying 30 a loose bobbin, with a tension and thread-guide so arranged as to deliver the thread without disturbing its twist in either direction. More particularly my invention is as follows:

As before stated, this shuttle is in two parts 35 or shells, A and B, both semi-spherical in shape and hollow, as shown. Shell A has the stem *a*, which is slotted at the end and provided with projections *b*, as shown in the enlarged view, Fig. 5, which forms a snap-catch to attach the shell A to shell B. The shell B has a 40 hollow spindle, *c*, which fits over stem *a* of shell A, and has the recesses *d* to receive the projections or catches *b* of stem *a*. By this construction the two shells are held together with 45 sufficient force, but may be separated by simply giving them a smart pull apart. To effect the revolution of both shells together, I provide the spindle *c* with one or more studs, *e*, and at a corresponding point in the shell A, I

locate one or more recesses, *f*, so that when the two shells are attached together the studs *e* and recesses *f* form a clutch or crab to insure simultaneous movement of the two shells. When thus locked together it will be observed that there is a slit between the rims of the two shells all the way around; but I prefer to have the shell B slightly larger than and overlapping shell A, for a purpose to be hereinafter explained. Shell B is provided with the loop-catcher or "horn" *g*, whose point is about on a line with the outer face of the shell, or slightly overhanging it, whence it retreats backwardly, in a slanting direction, to the rim or lip of the shell, so that once the loop is caught the revolution of the shell forces the loop to follow 65 along the inclined side of the horn *g* till the thread of the loop arrives at the rim of shell B, where it drops over the base of the horn, and which prevents it from slipping off the shuttle and dropping the stitch. After passing 70 the horn the thread of the loop glides over the rim of shell B, and as it cannot return it is compelled to slide around the shell A, or, to speak more correctly, the effect is that the revolution of the horn *g* draws the loop in such 75 manner as to envelop itself once every revolution. The overlapping of shell A by the rim of shell B renders this enforced path of the loop more certain, and renders it impossible 80 for the loop-thread to drop into the space between the shells.

Before setting the shells A B together the bobbin C (having sufficient thread wound upon it) is slipped over the spindle *c*, and the end of the thread brought out through the circumferential slit between the shell-rims. Bobbin C is loose upon the spindle *c*, so that while the spindle revolves as a part of shell B the bobbin may remain comparatively stationary, moving only enough to reel off its thread; but as 90 a continued revolving of the spindle *c* would by friction soon impart a continuous movement to the bobbin, I insert a sort of brake or tension inside the shuttle. This tension consists preferably of a piece of sheet-steel of the 95 form shown at Fig. 6, which is bent up to form the two eyes *i* to ride upon the spindle *c*, and the end portions of the blank are brought to

gether and form the spring-lips *k*, which bridge the bobbin *C*, as illustrated, the fork *l* being curved upwardly, as shown, under the lips *k*. The whole device *i k l*, I call the "tension and 5 thread-guide." In inserting the bobbin *C* into the shells, the tension and thread-guide is set on the spindle so as to straddle the bobbin. The thread of the bobbin is passed between the prongs of the guide-fork *l*, and then between 10 the two spring-lips *k*, which press the thread between them with a light pressure. The two shells are snapped together after bringing the end of the thread outside. The shuttle-thread 15 being brought up through the throat-plate, drawing it tight lifts the tension and guide *k l* into a vertical position surmounting the bobbin *C*, and in about that position it remains while the shuttle revolves, delivering the thread as it is needed, allowing the bobbin to reel it 20 off, but exercising a sufficient restraint upon the thread, and this without in any way twisting or untwisting the thread—a result of much importance and essential to the success of a rotary shuttle.

25 The exterior of shell *A* may have the groove or furrow *n*, retreating spirally from a point under and slightly to the rear of the point where the inclined edge of the horn *g* terminates, so as to lead the loop properly.

30 The shuttle may be revolved by a crab or claw catching in depressions on the face of shell *A*, but allowing such play that the loop may pass between the claw ends and the shell without obstruction.

35 It will be seen that the tension or pressure on the thread varies itself automatically according to the thickness of the thread used. A thick thread passing through the lips will pull much harder than a fine thread, and this is as 40 it should be in order to have a proper tension suited to the different sizes of thread. As no screws or other devices are used, but simply

the natural spring of the lips, the tension is self-acting in the truest sense, and I therefore call it "automatic." It is independent, for the 45 reason that it is not permanently attached to the shuttle, but is simply contained therein, and moves at its own rate of speed independently of the revolution of the shuttle. While it is perhaps a part of the shuttle, and is necessary to it, yet it is dependent for action solely upon the thread passing between its lips.

I claim as my invention—

1. The rotary shuttle composed of the two hollow shells *A B*, having a thread-opening between them, and a bobbin-spindle, one of said shells having the projecting horn *g*, substantially as described. 55
2. In a rotary shuttle, the shell *A*, having spring-stem *a*, provided with catches *b*, in combination with shell *B*, having horn *g*, and hollow spindle *c*, provided with recesses *d*, substantially as described. 60
3. The rotary shuttle composed of the two hollow shells *A B*, having circumferential 65 thread-opening between them, and a bobbin-spindle, shell *B*, having horn *g*, and constructed with its rim overlapping that of shell *A*, substantially as described.
4. In a rotary shuttle carrying an inclosed 70 bobbin, an automatic tension independent of the shuttle and inclosed therein, substantially as described.
5. In a rotary shuttle carrying an inclosed bobbin, an automatic tension and thread-guide 75 independent of the shuttle and inclosed therein, substantially as described.

In testimony that I claim the foregoing as my own I have hereto affixed my signature in presence of two witnesses.

THOS. B. ROBERTS.
